UNITED STATES PATENT OFFICE.

THOMAS P. SCHWARTZ, OF STOCKTON, CALIFORNIA.

COMBINATION-TOOL.

SPECIFICATION forming part of Letters Patent No. 433,098, dated July 29, 1890.

Application filed November 18, 1889. Serial No. 330,800. (No model.)

To all whom it may concern:

Be it known that I, THOMAS P. SCHWARTZ, a citizen of the United States, residing at Stockton, in the county of San Joaquin and State of California, have invented certain new and useful Improvements in Combination-Tools; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention has relation to improvements in Compound Tools; and it consists in the construction, novel combination, and adaptation of parts hereinafter described and claimed.

20 In the accompanying drawings, Figure 1 is a side view of the entire tool less the pipe-tongs attachment. Fig. 2 is a side view of the pipe-tongs attachment. Fig. 3 is a side view of the tool when in position for stretching wire. Fig. 4 is a side view when in position for use as pipe-tongs. Fig. 5 is a top view of the claw-hammer. Fig. 6 is a top view of the head of the extension-handle. Fig. 7 is a vertical longitudinal sectional view of the forward portion of the wrench-handle, showing the sliding head, also in section, in position thereon. Fig. 8 is a vertical cross-section taken on the line $x-x$ of Fig. 6, and Fig. 9 is a top view of the clasp c' .

35 Referring to the said drawings by letter, A represents an extension-handle, which may be used alone as a crow-bar or in combination, as shown, and it is provided at its outer end with a curved bifurcated toothed head A' , having slots a' or recesses cut in its respective bifurcated portions for the reception of lateral lugs g secured to the side of the wrench-handle portion B^4 , whereby a connection is effected between said extension-handle and the wrench-handle portion. This handle has T-grooves A^2 , in which slide the lugs of a clasp C' , having a loop attachment C and a roller C^2 at its head, which impinges upon a bench B^3 on the end of a wrench-handle B^4 , which handle is provided with grooves B^2 , in which slide the lugs of a head B' . The head of the hook C is inserted in a slot on the back

of the wrench-handle B^4 , which is also provided with a ratchet-back engaging with the edge of the inner under side of the head B' , the head B' being provided with a spring b , which when pressure has been brought to bear upon the forward portion of the head will permit the said head to move back and forth of the ratchet of the handle B^4 . The crow-bar or extension-handle A is provided with a corrugated head A' , and the handle B^4 is provided with a claw-head B , toothed on its inner side, and a hammer B^6 on its under side.

45 The above is a description of my compound tool as shown in Fig. 1, and as such it may be used as a wrench of various kinds and as a claw-hammer.

In Fig. 3 is seen the tool in use as a wire-stretcher for the purpose of building wire fences, &c. In this use the head B' is removed, the clasp C and hook C are placed in a horizontal position, and the hook C is inserted in a slot in the handle B^4 , the handle A being in an upright position. The claw of the head B will embrace the end of the wire, and any convenient object being used as the fulcrum, the handle A constituting the stretching-lever.

55 To use the tool as a pipe-tongs, as better shown in Fig. 4, I employ the handle A . The clasp C' , being removed and reversed, is placed at any convenient point in the T-slots A^2 . The roller C^2 then has a bearing beneath the handle. The hook C is connected by a chain D^2 to a pipe-tongs attachment D , which is hook-shaped and has a corrugated or toothed surface within the hook adapted to operate in conjunction with the corrugated head of the handle A and to be adjusted to various sizes of pipe.

60 Having described my invention, what I claim is—

1. The combined claw-hammer, wrench, and crow-bar comprising the extension-handle A , provided with the grooves A^2 , the clasp C' , roller C^2 , and hook C , the wrench-handle B^4 , provided with a ratchet-back and with the grooves B^2 , the head B' , provided with the spring b , the corrugated claw-head B , and hammer B^6 , all combined and operating as set forth.

2. In a compound tool, substantially as de-

- scribed, the combination, with a crow-bar or handle having T-shaped grooves along its handle and its head bifurcated and toothed on its face and provided with a transverse slot upon its opposite side, of a wrench-bar B⁴, having at its outer end a claw provided with teeth on its inner face, a hammer-head on its under side, the lateral lugs on its vertical sides to engage the slot in the head of 5 the crow-bar, a long slot in its top side, and a bench B³ at its inner end, and the clasp C', having lugs to engage the grooves in the crow-bar or handle, and the roller C² and hook C, secured to said clasp, substantially as and 10 for the purpose specified.
3. In a compound tool, the handle-bar A, provided with longitudinal grooves in its side 15

walls and the bifurcated curved head at one end, having teeth upon its curved face and a transverse slot cut in its opposite side, in 20 combination with the clasp C', having lugs to engage the grooves of the handle-bar and carrying the roller C² and hook C, the curved hook-shaped branch D, toothed on its inner side, and the chain for connecting said hook 25 portion D to the hook C, all adapted to operate substantially as described.

In testimony whereof I affix my signature in presence of two witnesses.

THOMAS P. SCHWARTZ.
